[57] **CLAIM**

The ornamental design for a hinge with protective cover therefor, as shown and described.

DESCRIPTION

FIG. 1 is a perspective view of a hinge with protective cover therefor showing my new design;

FIG. 2 is a side elevational view taken from the bottom of FIG. 1, the side opposite being substantially a mirror image;

FIG. 3 is a top plan view thereof, the bottom being unornamented;

FIG. 4 is a front elevational view thereof;

FIG. 5 is a rear elevational view thereof;

FIG. 6 is an exploded perspective view thereof;

FIG. 7 is a side elevational view of the protective cover, shown separately for ease of illustration, the side opposite being a mirror image;

FIG. 8 is a top plan view of FIG. 7;

FIG. 9 is a rear elevational view of FIG. 7;

FIG. 10 is a front elevational view of FIG. 7;

FIG. 11 is a bottom plan view of FIG. 7;

FIG. 12 is a perspective view of a second embodiment of the design of FIG. 1, the only difference being the structure along the sides;

FIG. 13 is a side elevational view taken from the bottom of FIG. 12.
